[57] CLAIM

The ornamental design for an electric range, as shown and
described.

DESCRIPTION

FIG. 1 is a front elevational view of an electric range showing my new design built into a cabinet frame;

FIG. 2 is a top-plan view thereof;

FIG. 3 is a rear-elevational view thereof;

FIG. 4 is a bottom-plan view thereof;

FIG. 5 is a right-side elevational view thereof;

FIG. 6 is a right-side elevational view thereof; and,

FIG. 7 is a front elevational view thereof without the cabinet
frame and with the addition of hot plate indicia in a display
panel thereof.The cabinet frame shown in broken lines in FIGS. 1, 3, 5 and
6 is shown for illustrative purposes only and forms no part
of the claimed design.
